UNITED STATES PATENT OFFICE.

HENRY BRINSER KEIPER, OF LANCASTER, PENNSYLVANIA.

CAR-HEATER.

SPECIFICATION forming part of Letters Patent No. 443,770, dated December 30, 1890.

Application filed March 3, 1890. Serial No. 342,522. (No model.)

To all whom it may concern:

Be it known that I, HENRY BRINSER KEIPER, a citizen of the United States, residing at Lancaster, in the county of Lancaster and 5 State of Pennsylvania, have invented certain new and useful Improvements in Car-Heaters; and I do hereby declare the following to be a full, clear, and exact description of the invention, such as will enable others skilled in the 10 art to which it appertains to make and use the same.

My invention relates to improvements in that class of car-heaters in which air is taken from the outside of the car, inducted into a 15 heating-chamber, and when heated distributed through the body of the car by means of flues or pipes extending along the sides of the car, said tubes provided with registers or openings between or under the seats, as in the 20 "Spear" system now in use.

The object of my invention is to heat and distribute a sufficient quantity of pure air without the use of the present coal or wood 25 burning stoves, accomplishing the purpose with greater economy, less care and attention, and the least possible risk from fire in case of accident. I attain the end sought in my invention by the means and devices illustrated in the accompanying drawings, in which—

30 Figure 1 is an inside elevation of a portion of a car, a heater embodying the elements of my invention appearing in longitudinal vertical section; Fig. 2, a full front elevation of the heater shown in Fig. 1; Fig. 3, an elevation of the rear side of Fig. 2, the back of the heating-chamber removed to show the arrangement of a series of horizontal heating-pipes or return-folds in place; Fig. 4, a top view of Fig. 2 with the rim of the top plate 35

40 around the combustion-chamber and the top of the heating-chamber removed; Fig. 5, a top view of the generating-coil and heating-folds detached from their respective chambers, the gage and air-vent pipe in horizontal 45 section; Fig. 6, an elevation of the lower portion of Fig. 5 viewed from the right; Fig. 7, a transverse vertical section, enlarged, through the heating-chamber and combustion-chamber, showing the heating-coil and gas-stove in 50 full lines, the partition dividing the heating-chamber in full elevation and the return loops or folds of the heater passing through

said partition in cross-section; and Fig 8, a top view, also enlarged, of the lower coil of the heater and the lower fold of the return-loops, 55 showing the junction of said heater-coil and loops on the right, the feed or outlet-pipes in place.

Similar letters and figures refer to similar parts throughout the several views.

A designates a portion of the inside of a car, showing my heating device in place in an angle of said car.

A' represents a cold-air-induction pipe from the outside of the car to the heating-chamber, 65 a being a damper by which the flow of said air may be regulated; A², a hot-air-distributing tube, provided with registers a' between contiguous seats, while a² designates a pipe connecting said tube with the heating-chamber. 70 This pipe and tube are of the ordinary construction now in use, and form no part of my invention, but are used in combination therewith.

B designates the combustion-chamber provided with a door b for convenience in lighting the stove; B', a suitable base supporting said chamber, and provided with orifices b' for the admission of air thereto; B², the top plate covering the combustion-chamber, 80 and provided with orifices b² to aid combustion, and B³ the heating-chamber fastened against the back, extending more than half-way around and from the top to near the bottom of the combustion-chamber, while a partition-wall b³, extending from the bottom to near the top, divides said heating-chamber into two compartments, conducting the air from the inlet first up over said partition and then down to the outlet into the distributing- 85 tube.

C designates the generator, consisting of tubular stand formed of spiral coils placed vertically in the combustion-chamber, extending from near the bottom to near the top of 95 said chamber, said coils narrowing gradually from the center, where the diameter is greatest, toward the top and bottom, where the diameter of the stand is very small. This form is given to receive more readily the action of 100 the heat from the flame of the stove placed below. The top and bottom coils extend radially outward through the wall of the combustion-chamber into the heating-chamber,

where they are joined to the ends of the heater C', consisting of a series of loops or return-folds of tubes placed horizontally, forming one continuous but tortuous pipe without end.

5 These loops or return-folds pass through the partition b³, Figs. 2, 3, and 8. The top of the generator at its center is provided with a smaller pipe D, extending vertically upward through the top plate of the combustion-chamber, and has attached a water-gage d, a steam-gage d', and at its extremity a pet-cock d². The water-gage indicates the height of the water when the generator is being filled, the steam-gage the pressure, should there be any, and the pet-cock is opened to reduce the pressure, also to let out the air when the generator and heater are being filled with water. The lower end of the heater just before the pipe re-enters the combustion-chamber is provided with a downwardly-extending pipe E, passing through the bottom of the heating-chamber and through the floor to the outside of the car, where it terminates in the threaded end e, where a hose may be attached to fill the generator and heater, the pipe E being provided with a valve 1 to stop the admission of water. The pipe E above the valve 1 is also provided with a pipe E', projecting horizontally forward, provided with a valve 2 and terminating in the threaded end e', where a hose may be attached when it is desired to fill the generator and heater from within the body of the car.

35 A gas-stove F (or a vapor-stove of some other kind) of sufficient capacity is placed under the generator in the combustion-chamber, as shown. This stove has its arm f extending rearward, said arm being provided with a suitable end f' to be connected by means of hose or pipe with the reservoir containing the gas (or other substance) being carried in the usual manner under the body of the car.

40 My method of heating is as follows: Having filled the generator and heater with water by either pipe E or E' till the water shows in the crystal gage d, when its inflow is stopped by closing the respective valve 1 or 2, and having also closed the pet-cock d² it will be readily seen that the water therein will be hermetically confined and not subject to waste from evaporation or other means. A small quantity of water is all that is required, say, from two to three gallons. Now, lighting the 45 stove F, the flame will strike the base of the generator and heat the water therein contained, which will rapidly rise, following the course of the spiral coil to the top and enter the heating-chamber, then following the

course of the horizontal folds of the heater C' 60 downward to the inlet will re-enter the combustion-chamber, where, becoming heated again and pursuing the same course, it will continue to circulate and carry heat continually to the heating-chamber. Again, the 65 motion of the moving car will continue to induct currents of fresh air into the heating-chamber B³, where coming in contact with the heater C' it will become heated, and passing first upward over the partition-wall b³, then 70 downward to the outlet and through the connecting-pipe a² into the distributing-tube A², and by means of the registers a' be distributed through the body of the car. It will be readily observed that this flow of air will be 75 continuous unless checked; also, that it may be regulated at pleasure by means of the damper a.

Having thus described my invention, what I do consider new, and desire to secure by 80 Letters Patent, is—

1. In a car-heater, the combination of a stove provided with a combustion-chamber and an air-heating chamber, a water-circuit consisting of a number of spiral coils located 85 in said combustion-chamber, the top and bottom of said coils having small diameters and the diameters of the successive coils gradually increasing toward the center, and return-folds located in said air-heating chamber, and 90 means for conveying air to the heating-chamber and from the heating-chamber to the cars, substantially as described.

2. In a car-heater, the combination of a stove provided with a combustion-chamber, 95 a gas or vapor stove in said combustion-chamber, and an air-heating chamber having a partition b³, a water-circuit consisting of a number of spiral coils located in said combustion-chamber, the top and bottom of said 100 coils having small diameters and the diameters of the successive coils gradually increasing toward the center, and return-folds located in said air-heating chamber and passing through said partition b³, and means for conveying air to said heating-chamber and from the heating-chamber to the car, the water-circuit provided with means for the injection of 105 water and the outlet of air, and with a water-gage and a steam-gage, substantially as described, and for the purpose set forth.

In testimony whereof I affix my signature in presence of two witnesses.

HENRY BRINSER KEIPER.
